TOY AIRPLANE SWING OR SIMILAR ARTICLE

Andrew W. Salter, Jr., Lakeland, Fla., and Richard J.
Freshwater, Denham Springs, La.

Application January 11, 1956, Serial No. 39,694

Term of patent 3½ years

(Cl. D34—15)

Fig. 1 is a perspective view, from the side, of a toy airplane swing or similar article, showing our new design.

Fig. 2 is a plan view of the same.

The side not shown has substantially the same appearance as the side shown in Fig. 1. The drawing figures are lined to indicate color contrast.

We claim:

The ornamental design for a toy airplane swing or similar article, as shown and described.
